UNITED STATES PATENT OFFICE.

ALBERT L. HENNESSY, OF DUNBAR, PENNSYLVANIA.

WINDOW-SHADE BRACKET.

1,082,591.

Specification of Letters Patent.

Patented Dec. 30, 1913.

Application filed October 7, 1912. Serial No. 724,394.

To all whom it may concern:

Be it known that I, ALBERT L. HENNESSY, a citizen of the United States, residing at Dunbar, in the county of Fayette and 5 State of Pennsylvania, have invented certain new and useful Improvements in Window-Shade Brackets, of which the following is a specification.

This invention relates to improvements in 10 brackets for window shades and curtains and has for its object to provide a detachable bracket support adapted to be adjusted to window casings of varying widths.

Another object of the invention is to provide 15 a shade bracket and window pole bracket supporting device adapted to be attached or detached to a window at will.

With the above and other objects in view I have invented the device illustrated in the 20 accompanying drawings in which,

Figure 1 is a front elevational view of a window partially broken away showing the application of my invention secured thereto, Fig. 2 is a front elevational view of the device detached from the window, Fig. 3 is a 25 rear elevation thereof, Fig. 4 is a section on line A—A of Fig. 3, and Fig. 5 is an enlarged detail view of a pole bracket.

Like reference characters indicate like 30 parts throughout the specification and in the several views in the drawings in which 1 indicates a window having an upper casing 2 to which a bracket supporting member 3 may be secured. The member 3 is provided 35 on its rear surface with a pair of transversely disposed jaws or clamping members 4 and 5 each of which consists of a pair of telescopically disposed toothed members 6 and 7 having longitudinally disposed slots 8. 40 The members 6 are provided with right angular upper ends 9 having teeth 10 thereon which are adapted to engage the upper surface of the member 2; and the members 7 are provided with lower right angular ends 45 11 having thumb screws 12 threaded therethrough to impinge upon the under surface of the member 2 whereby the member 3 may be securely fixed to the window frame. Screws 13 having enlarged heads 14 pass

through the slots 8 in both members 6 and 50 7 and project through the portion 15 of the member 3 and into the recess 16 therein and are engaged by the wing nuts 17, both nuts and screws being below the surface 18 of the member 3 so as not to interfere with the 55 shade 19 supported on the brackets 20 and 21, which are secured to the outer surface 18 of the member 3.

The two upper corners of the member 3 are provided with recesses 23 and 24 to receive 60 the saddles 25 and 26 which are formed integral with the curtain pole brackets 27 and 28 adapted to support the pole 29. The front sides 25' and 26' of the members 25 and 26 have thumb nuts 30 and 31 screwed 65 through them whereby said brackets may be securely fixed to the member 3.

By loosening the nuts 17 the members 6 and 7 may be slidably moved upon one another to adjust the clamps to a proper width 70 and when the said nuts are tightened upon the screws 13, the teeth 33 on the opposing surfaces of the members 6 and 7 interlock and hold said members rigidly connected.

By the use of this device the window casing 75 is not defaced by fixing brackets thereto and the window does not present an unsightly appearance when the shades and curtains are removed as the entire fixture and brackets may all be removed at will and almost instantaneously.

Having now described my invention that which I claim to be new and desire to procure by Letters Patent is:

1. In a device of the kind described the 85 combination of a bearing block, two slotted members, a rightangular offset formed upon one end of each slotted member, teeth formed on the edge of one of said offsets, said slotted members arranged to overlie each other, a 90 longitudinal series of teeth formed upon each member arranged to intermesh, a screw-bolt passing through said bearing block and both of said slotted members, and a jam-nut engaging said screw-bolt and said block 95 arranged to hold said members in mesh.

2. In a device of the kind described the combination of a bearing block, said block

being formed with a recess, two slotted members, a rightangular offset formed at one end of each of said slotted members, teeth formed upon the edges of one of said offsets, a screw - bolt passing through said slotted members and terminating in said recess, a jam-nut engaging said screw-bolt and arranged to be within said recess, and

shade-roller brackets mounted on said block substantially in alinement with said recess. 10

In testimony whereof I affix my signature in presence of two witnesses.

ALBERT L. HENNESSEY.
